UNITED STATES PATENT OFFICE.

CHARLES T. JONES, OF NEW YORK, N. Y.

DESIGN FOR A GLOVE-BUTTONER.

SPECIFICATION forming part of Design No. 14,15², dated August 7, 1883.
Application filed June 20, 1883. Term of patent 7 years.

To all whom it may concern:

Be it known that I, CHARLES T. JONES, a citizen of the United States, residing at the city, county, and State of New York, have invented and produced a new and original Design for Glove-Buttoners, of which the following is a specification, reference being had to the accompanying drawing, forming part thereof, in which the figure represents a plan view 10 fully illustrating my design.

The leading feature of my design consists in the configuration of the handle portion of the tapering loop or operative part, the same being formed to represent a miniature glove, with 15 its narrow or finger portion projecting toward

the narrow end of the loop, and arranged wholly or partially within the regular outline of the same, and forming the part grasped by the thumb and finger when operating it, the whole forming a unique, compact, and convenient shape suggestive of the use intended. 20

I claim—

The design for a glove-buttoner herein shown and described, the same consisting of the tapering loop, having the handle portion configured 25 to represent a miniature glove.

CHARLES T. JONES.
